EXTENSIBLE MAIL BOX

Henry Steen, Vashon, Wash.

Application January 31, 1933, Serial No. 654,381

5 Claims. (Cl. 232—17)

This invention has reference to improvements in mail boxes of the variety which may be extended to accommodate them to packages or articles of unusual length.

5 Its objects, generally stated, are:

To provide a mail box, normally of the dimensions which conform to the requirements of the United States Post-Office Department, but having a telescopic member engaging the body 10 of the box and provided with a door, and which member may be manipulated from the front of the box so as to extend the length of the box, thereby permitting it to receive objects or packages unusually long;

15 To provide in such a mail box, a catch device instrumental in extending said box to different and predetermined lengths, but which serves to limit the longitudinal movement of said telescopic member so that it may not be withdrawn 20 from the body of the box without disengaging said device; and,

To provide elements which render the box weather-proof when said box is in either extended or closed position.

25 In the accompanying drawing—

Figure 1 is a perspective of said mail box in extended position.

Fig. 2 is a longitudinal section of the same in telescoped position.

30 Fig. 3 is a cross section, drawn on the line 3—3, of Fig. 2, affording a front view of an upstanding projection of said catch device as located in its groove in the body of the box.

Fig. 4 is a cross section, drawn on the line 4—4, 35 of Fig. 2, showing, in an enlarged form, said catch device.

Fig. 5 is a view of a portion of Fig. 2 on an enlarged scale.

Referring more particularly to the drawing, 1 40 denotes the body of the mail box, which body is mainly conventional in form. As it may be noted particularly in Fig. 2, the bottom portion 2 of the body is provided with ends 3, bent right angularly and downwardly, which serve to elevate said portion slightly when it is secured in place, and also provide, in connection with the sides and rear end of the body, a bottom flange 4 for said body. The body 1 is closed at its rear 45 end and open at its front end, said front end, exclusive of the adjacent edge of the bottom portion 2, being provided with a beaded edge 5. 6 designates an integral and internal longitudinal groove formed in the top of said body, the 50 same constituting a part of the catch device re-

ferred to, and which will be particularly described in order.

A telescopic member, generally denoted as 10, has a body portion 11 of approximately the same length as said body 1 and snugly conformable thereto, the same, as is evident, being designed to telescopically engage said body. The rear end of the body portion 11 is at all times open, and its front edge is provided throughout with a bead 12, this bead purposely having a cross sectional area considerably larger than the beaded edge 5. Said member 10, includes at its front end, a door 13, which obviously permits the front end to be opened or closed, as desired. Said door is hingedly connected with the lower edge of the 15 body portion 11, as at 14, and carries a flange 15, which affords a weather-proof connection for the door with the bead 12. Said flange is of sufficient width and the heavier bead 12 causes the flange to be spaced away from the walls of the body portion 11 to such an extent as to also afford a weather-proof connection for said flange with the beaded edge 5 on the body 1, when said member 10 is fully telescoped within said body. 16 denotes a handle for manipulating 20 said telescopic member, and 17 designates generally, a retaining device for said door.

Said device comprises a member 20, made of relatively stiff spring material, fixedly secured at one end to the body portion 11 and bent so as to accommodate the beaded edge 5 and thereby permit the member 10 to be telescoped in closed position within the body of the box. The member 20 is also bent so that it may clear the door 13 and extend in an approximately horizontal position, the same being of a length which will permit it to project for a substantial distance beyond said door. The free end of the member 20 is upturned slightly, as at 21, to form a lip, and said member is provided with an upstanding bight portion 22 and an opening 23. A second member is provided for this device, the same including a body portion 24, fixedly secured to the door 13. Extending from said body portion 24 is a horizontally disposed portion 25 which carries a bight portion 26 and an opening 27 complementary to said bight portion 22 and opening 23. 28 denotes a fingerpiece depending from said body portion. Said bight portions function as retaining elements, when they contact as shown in Figs. 1 and 2, for keeping said door shut, and said fingerpiece obviously is useful in raising and lowering said door and in bringing said retaining elements into closed or open position. When the door is shut, the openings 23 and 27 are brought 55

into alignment, and a padlock may be installed therein, if desired.

Integral with the body portion 11 of said telescopic member are a plurality of external grooves 29, disposed in spaced parallel relation. Said grooves are adapted to provide, in cooperation with the beaded edge 5 of the body of the box, weather-proof connections for the body 11 of the member 10 with the body 1 of the box, when said member is in extended position, said grooves being designed to fit into said edge 5, obviously when brought into contact therewith, and thereby affording close fitting joints. Said grooves also subserve another useful purpose, in that they provide channels for diverting water downwardly so that it may more readily run off of the body of the member 10.

The catch device, previously mentioned, comprises a strip 30 of sheet spring stock, fixedly secured as at 31, to the underside of the top wall of the telescopic member 10. It is provided at its free end with an integral, right angular and pointed projection 32 which extends through a slot 33 in said top wall, the said projection being freely movable vertically in said slot. The projection 32 normally extends into and slidably engages the groove 6 in the body of the box, the front end of said groove serving to limit the forward movement of said projection therein, and thereby preventing the telescopic member from being wholly withdrawn from said body while the device is functioning as a mail box.

As is evident, the normal position of the point of the projection 32 is above the top of the body of the member 10. When inserting said member in the body of the box, said projection may be pressed downwardly by the finger so as to clear the beaded edge 5, then when said member is slid into said body, the projection, by virtue of the tension imparted to it through its retracted position and contact with the inner surface of the top of said body, will click into the groove 6, when said groove is reached. It is then in operative position, the projection riding back and forth in said groove, as the member 10 is moved inwardly or outwardly.

Assuming that the telescopic member is disposed completely within the body of the box, the device functions as an ordinary mail box, mail matter obviously being deposited after opening the door 13 by releasing the retaining device, through pulling on the fingerpiece 28. If it be desired to extend said telescopic member, this is done by pulling on the handle 16, said retaining device being effective in keeping said door closed against such action. When the mail box has been thus extended to the required length, said door may be then opened and a delivery made, as described.

60. To disassemble the member 10 from the body of the box, said projection may be released from said groove, by pulling down the strip 31 from interiorly of said member, when the parts may be easily separated.

65. While it is contemplated that this mail box when in telescoped condition may be of ordinary size, the construction described will permit, if desired, the provision of a mail box which is normally smaller than usual, its extensible feature, and weather-proof qualities whether the box is extended or not, imparting to it effective increased capacity as the same may be required.

Changes in and modifications of the construction described may be made without departing 75 from the spirit of my invention or sacrificing its

advantages, hence it is asked that I be not confined to the specific structure set forth, except as limited by the appended claims.

I claim:

1. An extensible mail box, comprising a body portion closed at its rear end and open at its front end, said front end having a beaded edge, a recess in said portion, a member telescopically engaging said portion, said member being open at its rear end and its front end, said front end having a beaded edge of greater cross-sectional area than the first-named beaded edge, a door hingedly mounted to the front end of said member, a flange carried by said door adapted to embrace the second beaded edge and provide a weather-proof connection for the door therewith, said flange having a width which will permit it also to embrace the first beaded edge and provide a weather-proof connection with the front end of the body portion when said member is fully telescoped within said portion, a retaining device for said door, and a catch extending from said member and slidably engaging said recess for limiting the longitudinal travel of said member. 10 15 20

2. An extensible mail box, comprising a body portion closed at its rear end and open at its front end, said front end having a beaded edge, an internal and longitudinal groove disposed in said portion, a member telescopically engaging said portion, said member being open at its rearward end and its forward end, said forward end having a beaded edge, a door hingedly mounted to the forward end of said member, a flange extending continuously along the side edge and top edge portions of said door and directed rearwardly, the first-named edge being so proportioned in size relative to the size of the second-named edge and said flange having a width and being of such a character as to provide a close contact for the flange with each of said edges when said member is fully telescoped within said portion, and a spring catch extending from said member and slidably engaging said groove for limiting the longitudinal movement of said member. 25 30 35 40 45

3. In an extensible mail box, a body portion closed at its rear end and open at its front end, said front end having a beaded edge, a member complementary to and telescopically engaging said portion for increasing the length of said box, said member being open at its rear end and its front end, a door, having a flange, swingingly connected with the front end of said member and providing a weather-proof closure therefor, said flange extending rearwardly of said door and adapted, when said member is telescoped within said portion, to embrace said edge and provide a weather-proof connection for said member with said portion, and a spring-actuated catch device to prevent said member from being inadvertently withdrawn from said portion. 50 55 60

4. In an extensible mail box, a body portion having a closed rear end and an open front end, said front end having a beaded edge, a member complementary to and telescopically engaging said portion for increasing the length of said box, said member being open at its rear end and provided at its front end with a beaded edge larger in cross-sectional area than the first-named edge, a door, having a flange, hingedly mounted to the front end of said member and providing a weather-proof closure therefor, said flange being adapted, when said member is telescoped within said portion, to cover, in close fitting engagement, the first-named edge, and a plurality of external 65 70 75 80 85 90 95 100

grooves carried by said member and located in spaced parallel relation, said grooves providing weather-proof connections for said member with the beaded edge of said portion when said member is in extended position.

5. In an extensible mail box, the combination of a main body portion having an open end provided with a beaded edge, an internal and longitudinal groove disposed in said portion, a member complementary to and telescopically engaging said portion, for increasing the length of said box, said member being provided with an opening

positioned oppositely of said groove and also a plurality of external grooves disposed in spaced parallel relation, said grooves being adapted to contact with said edge and afford weather-proof contacts between said portion and said member as the member is extended, and a spring retainer comprising a spring fixedly secured at one end within said member, said spring having an up-standing free end retractable within said opening and engageable with said groove.

10
